WOODEN PATCH MAKING MACHINE

Will Aubrey Forsyth, New Westminster, British Columbia, and William Arthur Davis, Vancouver, British Columbia, Canada; Jean Margaret Forsyth executrix of said Will Aubrey Forsyth, deceased

Application August 19, 1946, Serial No. 691,572

8 Claims. (Cl. 144—2)

1

In the plywood industry, particularly that in which softwoods such as Douglas fir and the like are used, it is found expedient to remove knots and other defects from the veneer and fill the hole resulting therefrom with a piece of wood cut to conform to the size and shape of said hole.

It is found desirable to use a patch of uniform size and to bevel its edges so that when it is pressed into place the patch will adhere to the surrounding wood so securely that the patched material may be handled without the patch becoming detached at any part of its periphery.

The object of the present machine is to cut wood patches of identical size and form for this purpose and to do so both rapidly and economically.

The invention contemplates means for feeding a strip of material, means for cutting the strip into identical lengths and devices for rounding and beveling the ends of said lengths as will be more fully described in the following specification, and the accompanying drawings, in which:

Fig. 1 is a plan view of the invention.

Fig. 2 is an end elevational view as viewed from the right of Figure 1.

Fig. 3 is a front elevational view.

Fig. 4 is a sectional view taken on 4—4 of 1.

Fig. 5 is a sectional view taken on 5—5 of 1.

Figs. 6 and 7 are detail views of the jaws of the patch grip shown open and closed respectively.

Fig. 8 is a transverse sectional detail view of the strip feed table.

Figure 9 is a perspective view showing a patch just after completion, and while still being held between the patch carrier and hold-down, the latter elements and cutters being shown by broken lines.

In the drawings like characters of reference indicate corresponding parts in each figure.

The numeral 1 indicates generally a frame having a front wall 2 and side walls 3 and 4 which are connected together at their base by a horizontal bearer 6 (see Fig. 5). Journalled between the side wall 3 and a horizontally disposed U-shaped bracket 7 secured to the side wall 4, is a drive shaft 9.

The drive shaft 9 is fitted outside the frame with a drive pulley 10 which is to be driven by a belt 11 from a suitable source of power, and is fitted within the frame with a worm 13, having operative engagement with a horizontally disposed worm wheel 15. The horizontal bearer 6 supports a vertical shaft 18 which supports a step and an upper bearing 19 and 20 respectively,

2

between which bearings a sleeve 22 is journalled.

The sleeve 22 is fitted with the worm wheel 15, an edge cam 23, a face cam 24, and a chain sprocket 25, all of which are rotated from the worm 13.

A stationary sleeve 27 surrounds the shaft 9 and is carried from the wall 3 and rockingly mounted thereon is a bell crank 28.

The bell crank 28 has arms 29 and 30. The arm 29 carrying at its outer end a roller 31 which rides on the surface of the face cam 24 and the arm 30 being forked as at 33 to engage one end of a connecting rod 34.

Mounted upon the front wall 2 are brackets 36 upon which a strip feed table 37 is detachably mounted, the feed table being provided with a channel 38 having inwardly inclined side walls 39 which conform to the side edges of the strip of material from which the patches are to be made.

A U-shaped bracket 42 is mounted upon the front wall 2 of the frame 1 for the purpose of swingingly supporting a circular saw 43. The saw 43 is mounted upon an arbor 44 which extends through a bearing 46 and is provided with a driving pulley 47.

The bearing 46 is carried at the upper end of a swinging arm 49 which is journalled within the bracket 42 on a shaft 50 carried by said bracket.

Pulleys 52 and 53 are coupled together and are journalled upon the shaft 50. The pulley 52 being connected by a belt or chain 54 to the saw driving pulley 47 and the pulley 53 being connected by a belt or chain 55 to a pulley 56 upon the main drive shaft 9 which in turn is driven through a pulley 10 by a belt 11 from any suitable source of power not shown. The bearing 46 is connected with the bell crank 28 by the connecting rod 34 thus completing the operating train between the drive shaft 9 and the saw arbor 44.

Mounted upon the front wall 2 is a vertical V guide 62 in which slide 63, having a strip receiving jaw 64, is mounted.

45 The slide is provided on its rear side with a forked lug 66 and is engaged by a lever 67 which is rockingly mounted on a shaft 68 carried between the vertical face of the U-shaped bracket 7 and the side wall 4.

50 The lever 67 is provided intermediate its length with a roller 70 which is adapted to ride in the groove of the edge cam 23.

55 The jaw 64 is provided with a convexly curved patch-supporting face 72 having front and rear ribs 73 with vertical inner faces 74 which are

spaced apart the full width of the patch material, i. e. the width of the lower face of the patch material as presented for processing in the channel 38 of the feed table 37 and as shown in Figures 6 and 7.

Slidably mounted in the jaw 64 is a non-rotatable stem 76 having a T head 77 which terminates at the front with a concave faced jaw 78 and at the rear with a lug 79. The lug is provided with a set screw 80 which is adjustably set to arrest the downward movement of the jaw 78 on its coming into contact with the top edge of the front wall 2 as shown in Fig. 4.

The stem 76 is threaded at its lower end as at 15 81 and provided with locknuts 82 between which the lower jaw 64 is a compression spring 83 which causes the jaw 78 to close upon a patch 84 and the jaw 64 when the slide 63 is raised to a point where the set screw 80 is raised out of contact with the edge of the front wall 2.

A pair of aligned rails 86 are mounted on the top edge of the front wall 2 upon which a pair of slides 87 are adjustably supported. These slides carry a journal housing 88 in each of which a spindle 89 is rotatably mounted.

Each spindle is provided with a pulley 90 at one end and a rotary cutter head 91 at the other.

The cutter heads are aligned above the path of the patch strip and are provided with knives 92 conforming to the shape of the ends of the patch to be cut, which in the present instance is semi circular. The cutter heads 91 are driven in opposite directions from a suitable source of power by belts 93 engaging the pulleys 90.

On the right end of the front wall 2 (as viewed in Fig. 3) an upward extension 96 is provided to support an elongated bearing 97 in which a shaft 98 is rotatably mounted. This shaft is fitted at its outer end with a quadrant 99 having patch engaging teeth 100, the peripheral length of the quadrant being equal to the patches to be cut.

The inner end of the shaft 98 is fitted with a bevel pinion 102 which meshes with a similar pinion 103 secured to a vertical shaft 104.

The shaft 104 is mounted in bracketed bearings 105, see Fig. 2, and is fitted at its base with a sprocket 106 through which it is driven by a chain 108 from the sprocket 25.

In operating the machine a strip of material which has been bevelled along its side edges is inserted into the channel 38 of the feed table 37 and is moved along until its leading end reaches the cut off position parallel with the saw 43 and the various prime movers are set in motion.

The sequence of operations performed by the machine occur in the following order. The strip is advanced one patch length, the leading end is projected between open jaws 64 and 78, the jaws then close and the patch is cut off by the saw. The jaws subsequently rise to advance the ends of the patch to the cutters until both ends are bevelled off and the patch is but slightly below the axes of the cutters, the saw returns out of the path of the patch strip, the jaws are lowered and opened and the quadrant 99 in rotating again engages the patch strip to advance it and push the finished patch from between the jaws.

For each complete rotation of the worm wheel 15 the quadrant also rotates once through the sprocket 25, the chain 108, sprocket 106, the vertical shaft 104, and the quadrant shaft 98.

The cam 24 in rotating once causes the bell crank 28 to rock rearwardly and forwardly, causing the saw 43 to swing in a corresponding direc-

tion to cut the patch strip and subsequently to swing out of its path.

The cam 23 in rotating once, first raises the lever 67 as its initial movement, lifting the jaw 64 until it causes the patch strip 84 to engage the jaw 78 when the compression spring 83 completes the grip upon the patch strip. Subsequent lift of the lever 67 raises the entire jaw assembly and the strip held therebetween. On the return movement of the lever 67 the jaws are lowered simultaneously until the set pin strikes the top edge of the wall 2 when the downward movement of the upper jaw 78 is arrested and the lower jaw is carried down further against the action of the spring 83 to separate said jaws and allow the oncoming strip to remove the finished patch from between them.

With the patch being transversely sprung when gripped between the jaws the bevelled side edges will be disposed vertically or parallel to each other, consequently each of the knives 92 of the cutters 91 which are provided with a half round cutting edge, will cut a bevel of maximum angle at the ends of the patch when said patch is fully elevated and the angle of the bevel of each end will decrease toward the side edges of the knives.

This decrease of angle is twofold, first because the side edges of the patch strip are further below the centre of the cutters than the longitudinal centre and secondly on account of the increase in radius of the side edges of the knives over the centre portion.

The result of this decrease, partly incidental to the transverse curvature of the patch strip causes the bevel cut by the knives to merge into the bevel of the edges of the strip, so that when said strip is released from the jaws and returns to a flat condition, the bevel is constant around its entire perimeter and it can be relied upon to fit perfectly a recess in the surface plane of a board which has been made by any appropriate mechanical process. The completed patch still in its bent position, held between the carrier and hold-down, appears in Figure 9.

A further object in the transverse distortion of the patch material is to provide said patch with such rigidity that the patch will stand up to the recurring impact of the knives without causing the fibre to be ragged.

What we claim as our invention is:

1. A patch making machine comprising means supporting and guiding a strip of patch stock for lengthwise advance, feed means operable intermittently to advance such strip by increments substantially equal to the length of a patch, cut-off means stationed along the line of advance and operable to sever a patch blank from the leading end of the strip following each incremental advance movement thereof, patch gripping means operable to clamp the severed patch blank by its opposite faces and hold it securely therebetween with its ends projecting clear of such gripping means, a pair of cutters; means supporting said cutters for rotation, respectively, about stationary, spaced, and parallel axes extending transversely of the line of patch stock advance and disposed in a plane generally parallel to, and spaced from, a plane containing either opposite face of the severed pre-clamped patch blank; said cutters having cutting edges of a length to trim the full width of the patch blank ends; and means operable to shift said gripping means and patch blank clamped therebetween toward said cutters in a direction normal to said planes, thereby to trim both blank ends simul-

taneously by the respective cutters, said shifting means being further operable to shift said gripping means and patch blank back into the line of patch stock advance to be ejected from the gripping means by the end of the patch stock strip when next incrementally advanced.

2. A patch making machine comprising patch gripping means operable to clamp an elongated patch blank by its opposite faces and hold it securely therebetween with its ends projecting clear of such gripping means, a pair of cutters; means supporting said cutters for rotation, respectively, about spaced, parallel axes extending transversely of the elongate axis of the patch blank and disposed in a plane generally parallel to, and spaced from, a plane containing either opposite face of the pre-clamped patch blank; said cutters having cutting edges of a length to trim the full width of the patch blank ends; and shifting means operable to effect relative approach movement between said cutters and said gripping means, while the patch blank remains clamped thereby, in a direction normal to said planes, thereby to trim both blank ends simultaneously by the respective cutters.

3. The patch making machine defined in claim 2, wherein the gripping means comprises a pair of coacting clamp elements formed with convex and concave surfaces, respectively, to clamp the patch blank tightly therebetween and thereby bend and stress the patch blank about an axis generally parallel to its length to a predetermined curvature; the cutter edges being formed with a predetermined concave rounding, related to the curvature of bending of the blank, to trim with half-round curvature the ends of the patch blank presented to such cutters; and means limiting progressive movement of the clamp elements toward the cutters, at a position of the patch blank appreciably before it reaches the plane containing the cutters' rotational axes, the curvature and radius of rotation of the cutters and the curvature of the blank being so interrelated that a substantially constant bevel is imparted to the rounded ends of the patch blank.

4. In a patch making machine, a pair of jaws having cooperating convex and concave surfaces, respectively, said jaws being operable to grip a generally flat patch blank and on the closing of said jaws being operable to bend the patch blank under stress about an axis extending lengthwise of its grain; a cutter for beveling one end of the patch blank; said cutter being rotatable about an axis extending transversely of the patch blank's grain and substantially parallel to a plane containing the pre-bent flat surface of the patch blank, and means operable to effect progressively relative approach movement of said jaws and said cutter while the jaws thus grip the patch blank, for bringing such blank into progressive cutting contact with said cutter while maintaining said parallel relationship of the cutter axis and said plane.

5. A patch making machine comprising a frame, a carrier supported by said frame for carrying a patch blank thereon having opposite ends to be cut to desired shape, gripping means operable to hold such patch blank on said carrier, a pair of driven cutters having relatively wide transverse cutting edges which are shaped to impart corresponding configuration to respective opposite ends of patch blanks cut thereby, means supporting said driven cutters to rotate about spaced parallel axes disposed generally perpendicular to the length of the gripped patch

5

blank between said ends thereof and lying in a plane generally parallel to the opposite faces of such blank, and shifting means operable to effect relative approach movement between said cutters and the patch blank held on said carrier by said gripping means in the direction perpendicular to said plane, for presenting simultaneously both ends of the patch blank to the respective cutters to be cut simultaneously thereby to the configuration of said cutting edges.

6. The patch making machine defined in claim 5, in which the peripheries of the cutters are concave in cross section for cutting convexly rounded ends on the patch blank.

7. In a patch making machine, a pair of jaws having cooperating convex and concave surfaces, respectively, said jaws being operable to grip a generally flat patch blank elongated parallel to its grain and, on the closing of such jaws being operable to bend the patch blank under stress about an axis extending lengthwise of its grain; a cutter for beveling one edge of the patch blank, said cutter being rotatable about an axis extending transversely of the patch blank's grain and substantially parallel to a plane containing the pre-bent flat surface of the patch blank; means operable to advance said jaws progressively toward such cutter in a direction transversely of the patch blank while the jaws thus grip the patch blank, for bringing such blank into progressive cutting contact with said cutter while maintaining said parallel relationship of the cutter axis and said plane; and means terminating such progressive advance of said jaws before the blank reaches a plane parallel to the first mentioned plane and containing the cutter's rotational axis.

8. A patch making machine comprising a grooved member supporting and guiding for lengthwise advance a strip of patch stock having oppositely beveled side edges, the groove of said member being of dovetail cross section and receiving the beveled strip in dovetailed interlocking and relative sliding engagement, feed means operable intermittently to advance such strip by increments substantially equal to the length of a patch blank to be cut, cut-off means stationed along the line of strip advance and operable to sever a patch blank from the leading end of the strip following each incremental advance move-

ment thereof, gripping means operable to clamp the severed patch blank by its opposite faces with its ends projecting clear of such gripping means; a pair of cutters, means supporting said cutters for rotation, respectively, about spaced, parallel axes extending transversely of the line of patch stock advance and disposed in a plane generally parallel to and spaced from, a plane containing either opposite face of the pre-clamped patch blank; and means operable to effect relative approach movement between said cutters and said gripping means, while the patch blank remains clamped therebetween, in a direction normal to said planes, thereby to trim both blank ends simultaneously by the respective cutters.

WILL AUBREY FORSYTH.
